UNITED STATES PATENT OFFICE

SAMUEL A. GILBERT, OF CHICAGO, ILLINOIS

FLASH LIGHT

Application filed March 7, 1929. Serial No. 345,159.

My invention relates to pocket flashlights which are commonly operated by internal batteries, and more particularly to the head piece of the article and my main object is to provide a head piece which is adjustable as to position yet remains in the close and compact position of the conventional head piece under normal conditions.

A further object of the invention is to construct the novel head piece with an extensible connection from the body of the flashlight, whereby to permit the sufficient departure of the head piece from the body for various adjusting movements.

15 A final, but nevertheless important object of the invention is to design the novel flashlight on lines of exceeding simplicity, whereby to enable the same to be produced at low cost.

20 With the above objects in view, and any others that may suggest themselves from the specification and claims to follow, a better understanding of the invention may be had by reference to the accompanying drawing, 25 in which—

Figure 1 is an elevation of the novel flashlight, showing by means of dotted lines the extended and adjusted positions of its head piece;

30 Fig. 2 is an elevation, partly in section, showing the normal position of the head piece and its electrical connections; and

Fig. 3 is a perspective view of the element connecting the head piece with the body of the flashlight, the head piece being indicated by dotted lines.

I am aware of the fact that flashlights have heretofore been devised with head pieces which are adjustable to different positions 40 in order to cast the light into places not ordinarily accessible when the flashlight body is rigid with the head, but in the instances which have come to my attention, the head piece was either bunglesome, distorted, or involved various connections or parts of a delicate or unstable nature. Also, in most cases the special nature of the head piece appeared to make the cost of the article prohibitive. It has been my intention to provide an improvement which efficiently ac-

complishes the objects outlined in a simple and inexpensive structure.

Referring specifically to the drawing, 10 denotes the body shell, 11 the battery unit, 12 the head piece, and 13 the illuminating element of a typical pocket flashlight.

In carrying out the invention, I construct the head piece 12 of the same tubular nature as the body shell 10, but separate from the latter. Under normal conditions the head piece is but a continuation of the body, as clearly shown in Figure 2, not occupying any more room than the conventional head piece. For the purpose of extending the head piece from the body, I provide on opposite sides 60 metal strips 14, these being riveted at their forward ends to the head piece as indicated at 15. Their rear ends are, however, longitudinally slotted as indicated at 16 to receive rivets 17 extended from the body shell 10, this relation rendering the strips 14 slideable upon the latter with some friction. Thus, should the head piece be extended from the body as indicated by the dotted lines 65 at the top of Figure 1, the extensible connection will be sufficiently stiff to maintain the head piece in the new position. However, the head piece could, when in this position, be swung over in one or the other direction to a position at the side of the flashlight, 70 as indicated by the dotted line shown at the extreme left of Figure 1. The rivets 15 are semi-tight, permitting the head piece to be 75 swung relative to the strips 14 in any direction, such as indicated by the lowermost dotted lines in Figure 1.

By extending the head piece from the body of the flashlight, it not only secures sufficient room to swing as shown, but may itself be adjusted in one or another position while only 80 extended and not swung as at the top of Figure 1, the extensive departure of the head piece lending it enough room to be pivotally turned on the rivets 15 in any direction 85 desired.

By constructing the body shell 10 and the head piece 12 of insulation, such as hard rubber or bakelite, I am able to use the strip 14 as electrical connectors of opposite polarities. Thus, the rivets 17 receive leads 18 and 90 95 100

19 from the battery terminals to the respective strips 14; and the rivets 15 are extended with contact stems 20 and 21 leading, respectively, to the center and external terminals of the illuminating element.

5 It will be apparent that in addition to the many adjustments of the head piece as made possible by my construction, two features are of prime importance. One is that the head piece in restored or normal position is virtually a part of the flashlight body and is quite as compact as the conventional flashlight head piece; and the other feature is that but the simple strips 14 and their connections are visible on the exterior of the flashlight body, no special wires or other connections being apparent for purposes of fastening any parts or transmitting the electrical current. It is significant when the second 10 feature is considered, that the electrical connections remain made or complete at all times, whether the head piece is compact with the body of the flashlight or extended or otherwise positioned. Thus, no special concern 15 need be given to the electrical make-up of the article, as the novel connections are simple, firm and dependable; also, they are at no time prejudiced or affected by the movements of the head piece, and the user may handle or 20 adjust the head piece without any concern 25 whatever as to the electrical connections.

I have illustrated the end portions of the flashlight with the usual corrugated ferrules 22 of sheet metal, but it will be noted that the 30 ferrule applied to the head piece is in no way connected or in the way of the current-conducting strips 14, and may be considered as extraneous.

As to the operation of the flashlight, the 40 improved head piece may be considered as fully connected as the conventional head piece, it being necessary to operate the switch button 23 in order to flash or extinguish the illuminating element.

45 While I have illustrated and described the invention in the preferred form, it will be evident that the same is capable of minor changes and refinements, and I desire to include such changes and refinements as coming within the spirit and scope of the appended claims.

I claim:—

1. A flashlight comprising a body portion, a head piece applied to one end of the latter, and links connecting the head piece with the body portion, the links being slidable upon the external surface of the body portion.

2. A flashlight comprising a body portion, a head piece at one end thereof, links longitudinally spanning the head piece and the body portion, rivets connecting the corresponding end portions of the links to the head piece, the other end portions of the links being longitudinally slotted, and rivets applied by way of the slots in such other end

portions to connect the latter to the body portion.

3. A flashlight comprising a body portion, a head piece endwise of and separate from the latter, links extended from opposite sides of the head piece upon the body portion, and an extensible connection between the links and the body portion.

In testimony whereof I affix my signature.

SAMUEL A. GILBERT.
